GUEDEL MANUFACTURING CO., INC., OF PORTLAND, INDIANA, A CORPORATION
OF INDIANA.

SMOKER'S PIPE.

1,417,823.

Specification of Letters Patent. Patented May 30, 1922.

Application filed October 25, 1920. Serial No. 419,177.

To all whom it may concern:

Be it known that I, CHARLES F. GUEDEL, a citizen of the United States, and a resident of Indianapolis, in the county of Marion and State of Indiana, have invented certain new and useful Improvements in Smokers' Pipes, of which the following is a full, clear, and exact description.

The invention relates to smokers' pipes and its object is to provide a pipe in which provision is made whereby the draft duct may be thoroughly and easily cleaned.

The invention consists in the novel features hereinafter set forth and more particularly defined by claim at the conclusion hereof.

In the drawings: Fig. 1 is a longitudinal section of a pipe embodying the invention. Fig. 2 is a similar view showing the manner in which the duct in the stem may be cleaned.

The invention is exemplified in a pipe comprising a stem 4 and a body 5 provided with a bowl for the tobacco and to which the stem is removably secured in usual manner. The bottom of the bowl is integral with the body. A duct 6 extends from the bottom of the bowl and through the stem and an opening 6^a extends from the bottom of the bowl through the front of the bowl in substantial alignment with the duct in the stem where it intersects or enters the bowl-chamber. A screw-plug 7 is adapted to normally close this opening. When the plug is removed, a cleaner can be passed entirely through the duct in the stem in either di-

rection. When a cleaner is inserted into a duct which is closed or obstructed at one end, the cleaner must be inserted in one direction and withdrawn in reverse direction, and more or less of the deposited matter in the 40 stem, which may be removed by the cleaner during insertion, will be re-attached to the stem during withdrawal. By providing means which permits the cleaner to be passed entirely through the pipe, the accumulation 45 in the stem will be thoroughly removed.

The invention is not to be understood as restricted to the details set forth, since these may be modified within the scope of the appended claim, without departing from the 50 spirit and scope of the invention.

Having thus described the invention, what I claim as new and desire to secure by Letters Patent, is:

A pipe comprising a body provided with 55 a bowl and a stem having a draft duct therein extending transversely to and having its inner end intersecting and completely open to the bottom of the chamber in the bowl, the body having a transverse opening having its 60 inner end intersecting and completely open to the bottom of said chamber extending through the front thereof and in substantial alignment with the duct in the stem to permit a cleaner to be passed directly and 65 completely through the stem and the bottom of the chamber in the bowl, and removable means for closing said opening.

CHARLES F. GUEDEL.
